8 Claims. (Cl. 91—12.2)

This invention relates to a method of and furnace for coating steel or like pipes internally with other metals, for instance copper, and the invention consists essentially in rolling the pipes 5 intermittently over a stepped support through a heating furnace.

For this purpose the furnace is provided with a heating chamber having a stepped bottom, and means are provided for rolling the pipes along 10 said bottom by pushing them from one step on to another. Means are also provided for tilting the pipes in order to discharge superfluous coating metal, and for cooling the pipes after the cooling process.

15 Fig. 1 of the accompanying drawings represents a sectional view of a furnace constructed according to the invention,

Fig. 2 is a section at right angles to Fig. 1.
Fig. 3 is a section on the line 3—3 of Fig. 2.

20 Fig. 4 is a diagram showing a modification of the stepped bottom of the heating chamber, and

Fig. 5 is a sectional view like Fig. 1 showing a modified arrangement.

The furnace is provided with a heating chamber 25 the inlet to which is permanently closed in order to prevent loss of heat and in order to retain the protecting gas which maintains the heated pipes in polished condition. The closing element consists of a feeding roller *a* which is 30 rotatably fitted in the inlet and provided with longitudinal grooves *b* in which the pipes are placed for introduction by means of a roller into the heating chamber. The roller forms a complete closure of the inlet even when it is 35 rotated. The pipes *f* are delivered by the roller on to a platform *c* which is wide enough to hold several pipes at the same time. The platform *c* is developed into a stepped chamber bottom down 40 which the pipes are fed.

45 The feeding mechanism comprises a vertical shaft *d* fitted with cams or eccentrics *e* for reciprocating a plurality of push rods *e'* which are slidably arranged and adapted to move across the steps for rolling the pipes from one step 50 on to another. The rate at which the shaft is driven depends on the time required for melting the coating metal. The steps *g* may differ as regards vertical and horizontal dimensions, as indicated in Fig. 4. This is of advantage as regards uniformity of the coating since it ensures that the pipes will drop on to the steps with different bearing surfaces and prevent the molten metal from accumulating continually along the same pipe portion.

55 The chamber is preferably heated by means

of electric heating elements *h*, but it can also be adapted for heating by means of gas or solid fuel.

After having rolled through the heating chamber in this manner, the pipes are brought into 5 an inclined position for the discharge therefrom of superfluous coating metal. For this purpose the pipes are discharged from the last step *g* into a downwardly inclined channel *k*. This channel contains an inclined roller *l* which receives the pipes, tilts them through an angle of about 90° and delivers them in this position into 10 an inclined delivery channel *m*. The roller *l* is hollow and cooled so that the temperature 15 of the pipes will fall rapidly below the melting point of the coating metal. A conveyor *n* is arranged so as to receive the pipes from the delivery channel and place them once more in a horizontal position. The conveyor moves the 20 pipes slowly through the furnace while still under the influence of the protecting gas and delivers them, after they have been subjected to further cooling, into a water bath of normal temperature.

There may be two separately fed heating chambers in the same furnace arranged as indicated 25 in Fig. 3.

When the pipes are to be provided with a particularly thick coating, they are charged with the required quantity of coating metal, and means are provided for using up all the metal in the 30 coating. For this purpose the arrangement shown in Fig. 5 may be employed. In this arrangement the heating chamber is adjoined by a cooling chamber *p* provided with an inclined delivery plane *q*. The first portion of the cooling chamber is comparatively hot, but the succeeding portion of the plane is exposed to cooling sprays *r* of water or air so that the coating metal will be caused to solidify. Owing to the 35 continuous rolling motion of the pipes, the coating will be uniform throughout. Uniformity of coating is particularly necessary when the pipes are subsequently to be subjected to a drawing operation.

40 From the plane *q* the pipes are delivered into a drum *s* which is open at the top and which dips with its lower portion into a water bath *t*. In this drum the pipes are subjected to further cooling, and when the drum contains a suitable number of pipes it is rotated for discharging 50 the pipes into the bath *t* for final cooling.

In order to maintain the pipe surfaces free from corrosion, the entire furnace system is charged with a protecting gas. While the inlet is permanently closed by the roller *a*, the outlet 55

is permanently closed by the water bath *t*, so that no escape of the gas is possible.

It should be observed that it has already been proposed in connection with a furnace for enamelling pipes internally, to roll the pipes gradually along an inclined plane. The characteristic feature of the invention is that the bottom of the heating chamber is stepped and that the pipes are fed intermittently from one step on to another. The number of steps is dependent on the desired efficiency of the furnace, the greater the number of steps the greater will be the efficiency.

I claim:

1. A method of coating pipes internally with metal comprising subjecting the pipes internally charged with coating metal to heat sufficient to melt the coating metal and simultaneously rolling said pipes in horizontal position and intermittently down a series of approximately vertical positions to cause the molten coating metal to apply itself uniformly over the interior of said pipes.

2. A method of coating pipes internally with metal comprising subjecting the pipes internally charged with coating metal to temperature sufficient to melt said coating metal, intermittently rolling said pipes while they are exposed to said heat in horizontal position down a series of approximately vertical positions to cause the molten coating metal to apply itself uniformly over the interior of the pipes, tilting the pipes out of horizontal position to drain off surplus molten coating metal, and subjecting the pipes to further rolling in horizontal position while they are exposed to a somewhat lower temperature.

3. A method of coating pipes internally with metal comprising subjecting the pipes internally charged with coating metal to a temperature sufficient to melt said coating metal, intermittently rolling said pipes while they are exposed to said heat in horizontal position down a series of approximately vertical positions to cause the molten coating metal to apply itself uniformly over the interior of the pipes, and subjecting the pipes to further rolling in horizontal position and to simultaneous cooling to solidify the coating.

4. An oven for internally coating pipes with molten metal comprising a chamber extending obliquely downwardly through the oven, said chamber having its bottom formed with a series of steps capable of supporting the pipes, means for introducing the pipes charged internally with coating metal and in horizontal position onto the uppermost step of the chamber bottom, means acting intermittently and transversely to the pipes on said steps to roll the pipes to the edges of the steps whereby they fall by gravity from one step to the next, means for subjecting the pipes to heat above the fusion heat of the coating metal while the pipes are rolling down said steps, and means for discharging the pipes from the lowermost step to the outside of the oven.

5. An oven for internally coating pipes with molten metal comprising a chamber extending obliquely downwardly through the oven, said chamber having its bottom formed with a series of steps capable of supporting the pipes, means for introducing the pipes charged internally with coating metal and in horizontal position onto the uppermost step of the chamber bottom, means acting intermittently and transversely to the pipes on said steps to roll the pipes to the edges

of the steps whereby they fall by gravity from one step to the next, means for subjecting the pipes to heat above the fusion heat of the coating metal while the pipes are rolling down said steps, an inclined channel below said steps, and an inclined roller arranged to receive the pipes from the lowermost step, tilt said pipes out of horizontal position and direct them into the channel. 5

6. An oven for internally coating pipes with molten metal comprising a chamber extending obliquely downwardly through the oven, said chamber having its bottom formed with a series of steps capable of supporting the pipes, means for introducing the pipes charged internally with coating metal and in horizontal position onto the uppermost step of the chamber bottom, means acting intermittently and transversely to the pipes on said steps to roll the pipes to the edges of the steps whereby they fall by gravity from 10 one step to the next, means for subjecting the pipes to heat above the fusion heat of the coating metal while the pipes are rolling down said steps, an inclined channel below said steps, an inclined roller arranged to receive the pipes from 15 the lowermost step, tilt said pipes out of horizontal position and direct them into the channel, and a horizontal conveyor below the channel arranged to receive the pipes and carry them in 20 horizontal position out of the oven. 30

7. An oven for internally coating pipes with molten metal comprising a chamber extending obliquely downwardly through the oven, said chamber having its bottom formed with a series of steps capable of supporting the pipes, means for introducing the pipes charged internally with coating metal and in horizontal position onto the uppermost step of the chamber bottom, means acting intermittently and transversely to the pipes on said steps to roll the pipes to the edges 35 of the steps whereby they fall by gravity from one step to the next, means for subjecting the pipes to heat above the fusion heat of the coating metal while the pipes are rolling down said steps, an inclined channel below said steps, an inclined roller arranged to receive the pipes from 40 the lowermost step, tilt said pipes out of horizontal position and direct them into the channel, and means for cooling the inclined roller. 45

8. An oven for internally coating pipes with molten metal comprising a chamber extending obliquely downwardly through the oven, said chamber having its bottom formed with a series of steps capable of supporting the pipes, means for introducing the pipes charged internally with coating metal and in horizontal position onto the uppermost step of the chamber bottom, means acting intermittently and transversely to the pipes on said steps to roll the pipes to the edges 50 of the steps whereby they fall by gravity from one step to the next, means for subjecting the pipes to heat above the fusion heat of the coating metal while the pipes are rolling down said steps, a cooling chamber communicating with the lower end of the oblique chamber and having its floor substantially continuous with and 55 downwardly inclined from the bottom of the lowermost step, means for cooling said inclined chamber floor, and means for discharging pipes from the lower end of said floor to the outside 60 of the oven. 65
